Des. 151,624

UTILITY CABINET

Filed Feb. 20, 1947

Inventor:

Roy C. Ingersoll

By Edward C. Putzbaugh Atty.

UNITED STATES PATENT OFFICE

151,624

DESIGN FOR A UTILITY CABINET

Roy C. Ingersoll, Winnetka, Ill., assignor to Borg-Warner Corporation, Chicago, Ill., a corporation of Illinois

Application February 20, 1947, Serial No. 137,036

Term of patent 7 years

(Cl. D33—19)

To all whom it may concern:

Be it known that I, Roy C. Ingersoll, a citizen of the United States of America and a resident of Winnetka, in the county of Cook and State of Illinois, have invented a certain new, original, and ornamental Design for a Utility Cabinet, of which the following is a specification, reference being made to the accompanying drawing, showing a front perspective view of a utility cabinet embodying my new design.

The essential features of my new design reside in the portions shown in full lines on the drawings.

I claim:

The ornamental design for a utility cabinet, as shown and described.

ROY C. INGERSOLL.
